(by his atty.)
William A. Powers

UNITED STATES PATENT OFFICE.

NICHOLAY JENSEN, OF WASHINGTON, DISTRICT OF COLUMBIA.

MATCH-SAFE AND CANDLESTICK.

SPECIFICATION forming part of Letters Patent No. 367,813, dated August 9, 1887.

Application filed September 29, 1886. Serial No. 214,858. (No model.)

To all whom it may concern:

Be it known that I, NICHOLAY JENSEN, a citizen of the United States, residing at Washington, in the District of Columbia, have invented 5 certain new and useful Improvements in Match-Safes and Candlesticks; and I do hereby declare the following to be a full, clear, and exact description of the invention, such as will enable others skilled in the art to which it appertains 10 to make and use the same.

The object of my invention is to furnish a combined candlestick and match-safe which can be constructed at a small cost and at the same time be neat in appearance, simple in 15 construction, and effective in its operation, and which can be carried in the pocket.

To this end my invention consists of certain arrangements and combinations of parts, which will be fully described in the ensuing specification, and clearly pointed out in the claims 20 at the close thereof.

In order that my invention may be clearly understood, I have illustrated in the accompanying drawings and will proceed to describe 25 a form thereof which I have used with practical success.

Figure 1 represents a perspective view of my invention with the cover in place. Fig. 2 represents an elevation of the same with the 30 cover removed and the match safe closed. Fig. 3 represents a vertical section through the opening in the match-safe. Fig. 4 represents an elevation with the cover removed and the match-safe open. Fig. 5 is a sectional view with 35 the cap or cover used as a base or holder. Fig. 6 is a sectional view of a match-safe of like construction.

The same letters of reference indicate identical parts in all the figures.

40 In the drawings, A represents a match-safe which consists of a tube closed at its lower end and provided with a partition, *a*, at or near its upper end. On the outside of the tube, and at a point intermediate its ends, is an annular flange or shoulder, *b*. In one side of the tube A, between the partition *a* and the shoulder *b*, is an opening, A', for taking out the matches and for refilling the match-safe when necessary. Over the upper end of the 45 tube A is fitted a sleeve, B, which is allowed to slide thereon a distance equal to the length of the opening A'. It will be noticed that the

lower end of the opening A' is a short distance above the shoulder *b*. The sleeve B, when in its lowest position, rests upon this shoulder, except that portion opposite the opening A', where the lower edge is bent inward in such manner that the inwardly-bent portion *c* rests upon the lower edge of the opening A', forming a close joint. This inwardly-projecting 55 portion *c* serves as a stop to limit the upward movement of the sleeve B.

In the upper end of the sleeve B is inserted, when desired, a candle, C, and a cap or cover, D, is provided to fit snugly over the sleeve B 60 when the candle is not in use. This cover is made to fit snugly against the flange or shoulder *b*. By placing a rubber ring upon the flange or shoulder *b* an air-tight joint is secured and the matches protected from moisture, even if by accident the device should be 65 immersed in water. The top of the cover D is provided with a roughened surface, *d*, on which the matches may be lighted.

I provide the sleeve B and cover D with a 70 double bayonet-joint, *e*. At one side of the opening A', I provide a small recess or open slot, *e'*. These constitute the means for retaining the parts in a closed position as the cap or cover D is forced down upon the sleeve 75 B. The opening into the bayonet-slot is made to engage the pin on sleeve B, and the sleeve B and cover D are then forced snugly down against the flange or shoulder *b*, when the cover is given a short turn, as though to screw the 80 parts together. This causes the pin to pass into the angular notch in the bayonet-joint and forces the projection *c* of the sleeve B in the recess or open slot *e'*, in which position 85 the parts will be held rigidly together. 90

When it is desired to open the match-safe, the cover D is moved sharply in the direction to unscrew the parts, which causes the pin *e* to pass to the left notch of the bayonet-slot, and the sleeve B is then turned so as to withdraw the parts *c* from the notch *e'*, in which 95 position the match-safe may be opened without exposing the candle.

The sleeve B and the lower end of the tube A are made of equal size, so that when the cap 100 or cover is taken off the candle it may be fitted on the lower end of the tube A, as shown in Fig. 5, and thus serve as a base or handle.

In Fig. 6 I have shown a match-safe without

a candle-holder. This box is made of two short pieces of tubes, one of which is closed at both ends and is provided with an opening, A', at one side. The other tubular portion 5 is closed at one end and is little larger than the other, fitting over the same. The lower edge of the outer portion is provided with the inwardly-projecting part e, the same as in the other construction. The inner portion is also 10 provided with the slot or recess e', whereby the two parts are locked in a closed position, and the longitudinal movement of the outer portion upon the inner is limited in the manner heretofore described.

15 The operation of the device will be apparent from the foregoing description.

I am aware that it has been proposed to construct match-safes of a metallic body closed at both ends and provided with a side opening 20 through which matches may be inserted and removed, with an outer sleeve moving on the body of the safe and serving to close the same when desired. I am also aware that such match-safes have been provided with a slot and 25 pin or groove and projection constructed to limit the movement of the covering-sleeve, and that a spring-catch has been employed to hold the sleeve and safe together when in a closed position. These constructions I do not 30 claim.

What I claim, and desire to secure by Letters Patent, is—

1. The combination, with a match-safe having an opening in one side for the insertion and 35 removal of matches and a holding-recess connected with the lower end of said opening, of a cover consisting of a sleeve mounted movably upon said match-safe and provided with a projection extending into the opening of the 40 match-safe, whereby the movement of the cover in either direction is limited and said cover may be locked, substantially as described.

2. The combination, with a match-safe closed at each end, having an opening at one side for the insertion and removal of matches, of the 45 sleeve mounted movably upon the match-safe and provided with a projection extending into the opening of the match-safe, whereby the movement of the sleeve in either direction is limited, substantially as described. 50

3. The combination, with a match-safe having an opening in one side for the insertion and removal of matches, and provided with an exterior flange between said opening and the lower end, of a sleeve movably mounted on 55 the match-safe over the opening, said sleeve being longer than the distance from the flange to the upper end of the match-safe, whereby said sleeve is made to close the match-safe and form a support for the candle, substantially as 60 described.

4. The combination, with a match-safe provided with an exterior flange, an opening above the flange, a sleeve mounted upon the match-safe over the opening and extending 65 above the match-safe, and a cover mounted movably upon said sleeve, substantially as described.

5. The combination, with a match-safe having an opening in its side and a holding-recess 70 connected therewith, of a sleeve mounted upon and extending above said match-safe, and provided with an inward projection, and a cover fitted upon said sleeve and connected to the same by a double bayonet-joint, substantially 75 as described.

In testimony whereof I affix my signature in presence of two witnesses.

N. JENSEN.
